UNITED STATES PATENT OFFICE.

GEORGE B. THOMAS, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

PUSH-BUTTON SWITCH.

1,102,967.

Specification of Letters Patent.

Patented July 7, 1914.

Application filed July 14, 1913. Serial No. 773,987.

To all whom it may concern:

Be it known that I, GEORGE B. THOMAS, a citizen of the United States of America, and resident of the city of Bridgeport, in the county of Fairfield and State of Connecticut, have invented a certain new and useful Improved Push-Button Switch, of which the following is a specification.

The object of my invention is to construct a simple and inexpensive form of push button switch, which at the same time will be efficient in its action. This object I attain by the construction which I will now describe.

In the accompanying drawing Figure 1 is a vertical section of my improved switch, showing the circuit open; Fig. 2 is a similar view showing the moving parts in other positions, with the circuit closed; Fig. 3 is a cross-section on the line 3-3, Fig. 1; Fig. 4 is a cross-section on the line 4-4, Fig. 1; Fig. 5 is a sectional plan on the line 5-5, Fig. 1; Fig. 6 is a section on the line 6-6, Fig. 1; Fig. 7 is a perspective view of parts detached.

The frame A on which the switch mechanism is mounted preferably consists of sheet metal bent into U-form at its upper part (Figs. 3 and 4), and with one of the legs of the U extended and bent into a foot piece a. To the bend of the U at the top is secured the face plate F while at the foot piece is secured the insulating bottom plate B. Between the face plate and bottom plate is held the rectangular casing C, forming with those two plates the inclosing box for the switch.

Between the two legs of the U of the frame A is mounted the switch lever 10 by means of a pivot pin 11, the metal of the legs being dented inwardly around this pivot pin to form small bearing faces 12 (Fig. 4) for the lever, thus avoiding the employment of the usual separate washers.

The lever 10 has pivotally connected to it the stems of the push buttons P, P¹, and one end of the lever is extended outwardly to carry the usual cross contact piece 13, insulated from the lever. On the insulating bottom plate are mounted two flexible con-

tacts 14 and 15 with terminal plates having 50 binding screws 16 on the outside for connection of the circuit wires. When the lever 10 is turned to the position shown in Fig. 2, the insulated contact piece 13 enters between the two contacts 14 and 15 and closes 55 the circuit. When the lever 10 is moved to the position shown in Fig. 1, the circuit is broken.

To give the requisite quick movement of the lever 10 in opening and in closing the 60 circuit, I form on the underside of the lever a projecting arm 17, which bears upon the upper end of a rod 19, preferably by forming a jaw 18 in the arm 17 to receive the bearing end of the rod, while at the same 65 time the rod itself is made with jaws 20, as seen in Figs. 4 and 7, to embrace the arm 17. These jaws 20 also coöperate with stops 21 on the frame A, which is notched out, as seen in Figs. 1 and 2, to provide the stops, to 70 limit the extent of throw of the upper end of the rod 19 and thereby the extent of throw of the switch lever. This rod 19 is shouldered at 22, Fig. 7, to bear through a washer 23 upon a coiled spring 25 around the stem of 75 the rod and bearing at its lower end upon the foot piece a of the frame A. The lower end of the rod 19 projects freely through an opening in this foot piece, as seen in Fig. 1, forming a fulcrum point on which the rod 80 and spring may swing from the position shown in Fig. 1 to that shown in Fig. 2, or vice versa.

It will be seen that the action of the arm 17 and rod 19 is that of a knuckle joint, the 85 coiled spring 25 pressing the rod 19 against the arm and tending to keep the parts in either position of rest, Figs. 1 and 2, but giving a quick impulse to the second half of the movement after the knuckle joint 90 passes the dead center in either direction.

I claim as my invention:

1. In a push button switch, a frame and a switch lever pivoted thereon, said switch lever having a jawed arm in combination 95 with a rod having a jawed end to coöperate with said arm and a coiled spring on said rod and pressing the latter against the arm.

2. In a push button switch, a frame and a switch lever pivoted thereon, said switch having an arm in combination with a rod having a jawed end to coöperate with said arm, stops on the frame to coöperate with jaws on the rod, and a coiled spring to act upon the rod.

In testimony whereof I have signed my name to this specification, in the presence of two subscribing witnesses.

GEORGE B. THOMAS.
